HAROLD F. VIEAU, OF LIVERPOOL, NEW YORK, ASSIGNOR OF ONE-THIRD TO ROY C. HIGBY, OF BIG MOOSE, NEW YORK, AND ONE-THIRD TO EDWARD J. O'NEILL, OF SYRACUSE, NEW YORK

CENTRIFUGAL CLOTHES DRIER

Application filed June 11, 1927. Serial No. 198,273.

This invention relates to a centrifugal apparatus designed primarily for the drying of clothes, but further capable for carrying out a rinsing operation with respect to the clothes when desired, and the invention has for its object to provide, in a manner as hereinafter set forth, an apparatus of the class referred to for expeditiously and satisfactorily drying clothes, as well as for automatically carrying off the extracted water simultaneously with the clothes drying operation, or when the clothes are subjected to rinsing.

A further and primary object of this invention is to provide, in a centrifugal apparatus, an overflow collecting and directing element for association with a centrifugal extracting receptacle to receive the overflow from the latter, and which is so constructed and arranged that the same may be manually adjusted to any position about the top of the receptacle so as to convey and direct the water or other fluid overflowing from the receptacle thereinto, to any one of a plurality of points, for example, into a washing tub, a bluing tub, or simply as waste water to any other receptacle or to a sink, or the like.

A further object of the invention is to provide, in a manner as hereinafter set forth, an apparatus of the class referred to with means for thoroughly rinsing a batch of clothes when desired, and with the rinsing water supplied from the bottom or top of said means and conducted therefrom during the rinsing operation.

While this device is illustrated as showing a mechanism for conducting rinsing water into the chamber through the bottom thereof, it should be understood that this feature is no part of the invention herein claimed, and that the adaptability of the receptacle as a rinsing receptacle is incidental to its primary purpose as a centrifugal drying apparatus. Further, that said receptacle is equally and as efficiently usable as a rinsing

receptacle without the water inlet mechanism, since that part of the device may be entirely eliminated and the rinsing water put into said receptacle by means of a bucket, hose, or the like, through the open top of the receptacle.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a side elevation of a centrifugal apparatus in accordance with this invention, showing the adaptation thereof, by way of example, with respect to a washing tank or tub.

Figure 2 is a top plan view of the same.

Figure 3 is a fragmentary sectional view of the upper portion of the centrifugal receptacle and adjustable overflow collecting and directing element associated therewith, taken on line 3-3 Figure 2.

Figure 4 is an enlarged fragmental detail view of one corner of the top of the centrifugal receptacle and adjustable overflow collecting and directing element to illustrate the exits for the overflow water between the receptacle and the lid therefor for the passage of the water to the collecting and directing element.

A centrifugal apparatus, in accordance with this invention, is illustrated by way of example in connection with a washing tank or tub for receiving the overflow from the centrifugal receptacle of the apparatus, but it is to be understood that the overflow can be directed to any other circumferential point

desired. As before stated the apparatus is designed primarily as a clothes drier, but can be, when desired, employed as a rinser.

There is illustrated a support, preferably a mobile one, for the elements of the apparatus. The support includes a platform 5, and a carriage 6. Mounted upon the platform and secured thereto is a washing tub 7 which, however, forms no part of this invention. Supported from the platform 5 is an electric motor 8 for furnishing the power to operate all of the mechanism connected with the washing tub or the drying apparatus. There is also carried by the support any suitable mechanism driven from the motor for transmitting a rotary movement to the drying mechanism, as well as any conventional type of control means which may be connected thereto for regulating said motor and said mechanism. The specific type of motor and power transmission mechanism shown and described more in detail hereinafter forms no part of this invention.

A receptacle 9, open at its upper end and preferably of inverted frusto-conical contour is rotatably mounted upon said platform and within said carriage as hereinafter described. Adapted to fit within the receptacle 9 is a foraminous basket 10 corresponding thereto in shape, but of less depth than said receptacle. The receptacle 9 is formed at its top with an outward extension 11, which terminates in a depending flange 12 spaced from the body of the receptacle. The upper face 35 of the extension 9 is transversely corrugated or grooved, as at 13, thus providing exits for the passage of overflow water or the like from the receptacle 9. The rotation of the receptacle 9, causes a centrifugal action which has the effect of extracting from a batch of clothes within the receptacle 9, any water or moisture in the clothes and discharging such water through the exits aforesaid. The arrows, Figure 4, indicate the direction of travel of 40 the extracted fluid upward along the inner wall of the receptacle to and through the exits to a manually adjustable overflow collecting and directing element to be presently described.

50 The receptacle 9 may be used with or without the basket 10. Said basket is formed with an enlarged reinforced upper rim circular in cross-section, as indicated at 14. This enlarged rim acts to space the basket from the inner wall of the receptacle. Said basket forms no part of the invention claimed herein.

Surrounding and extending above the upper portion of the receptacle 9 is a substantially vertical frame 15 and so formed at one portion of the periphery thereof that it may readily be secured to the washing tub 7 or other support. The inner wall of said frame is provided with a groove indicated at 65 16, while the upper edge of said frame acts

as a track for the manually adjustable collecting and directing element.

The manually adjustable overflow collecting and directing element is in the form of a combined trough member and drain board 70 and is generally designated as 17, is mounted above said frame 15, but is formed with an annular depending flange 18, said flange being adapted to seat snugly within said frame 15, and having in its outer peripheral wall a groove 19 adapted, when in position, to register with the groove 16, thus forming a race for the ball bearings 20.

The trough member is annular in form, having a bottom 21, an upwardly extending outer wall 22 integral therewith, an inwardly extending flange 23 integral with the top of said outer wall, and an upwardly extending inner wall 24 integral with the bottom 21. Said outer wall 22 is relatively higher with respect to the bottom 21 than is the inner wall 24. The outer wall 22 is cut away for a portion of its circumference as at 25, to provide an outlet for the trough member whereby the discharge from said trough member may be directed by a drain board 26 to any circumferential point desired. The drain board 26 is formed integral with the bottom 21 and outer wall 22, having upstanding side pieces 27 integral with the wall 22 at the ends of the 95 cutout portion 25.

When the receptacle 9 is set up in operative position with respect to the trough member, the depending flange 12 of the receptacle hooks over the inner wall 24 of the trough member, so that the extension 11 maintains a position in superposed spaced relation to the upper edge of the inner wall 24, while the depending flange 12 extends into the trough member. The trough member is circumferentially adjustable relative to the frame 15, so that the drain board 26 formed integral therewith may be manually adjusted to any selected circumferential point desired. When so adjusted the water or other fluid extracted by the centrifugal action of the receptacle 9 may be directed into the tub 7 or to any other vessel positioned at any point about the drying apparatus.

A cover 28, is adapted to seat upon the receptacle 9, the same being formed with reinforcing webs 29 on its upper face. The marginal portion of the cover member 28 is upset as at 30 to provide what may be termed an annular lip for seating on the top of the extension 11 of the receptacle 9. Said lip is so shaped with respect to the remaining portion of the cover as not to close the exits formed by the corrugations or grooves 13, as clearly illustrated in Figure 4 of the drawings.

The cover 28 is provided centrally of its outer face with a socket 31. The inner wall of the socket is formed with an offset or seat portion 32. An annular ring 33 is adapted to be inserted in said socket and rest upon the 130

seat 32 therein. Said ring is formed on its inner wall with a circumferential groove 34. The ring 33 is held within the socket by means of an apertured circular plate 35 preferably 5 in sections, said plate being seated on the upper edge of the wall of the socket 31 and overlying the top edge of the ring 33. Hold-fast elements 36 are then secured through the wall of the socket to the plate 35 to hold the same 10 in fixed position. A lid, hereinafter described in detail, is adapted to cooperate with the cover 28. Said lid is provided with a stub shaft 37 mounted centrally thereof, so positioned that the inner end thereof will 15 register with the socket 31 formed in the cover 28. The inner end of said shaft is reduced and screw threaded. Mounted on the shaft 37 above the inner end thereof is a ring 38 formed with an annular groove 39 in the 20 outer wall thereof. Said ring 38 is held upon said shaft by means of a lock nut 40. When in operative position, the inner wall of the ring 33 is opposed to the outer wall of the ring 38 so that the grooves 34 and 39 will 25 register to form a race for the ball bearings 41. This then permits the cover 28 to rotate freely with respect to the lid 42 upon which it is mounted.

The lid 42, previously referred to, is formed 30 laterally thereof with one section of a conventional hinge member, preferably having a pair of angularly disposed lugs 43 extending downwardly to be hingedly secured to the other section 44 of said hinged member, the latter being mounted to the frame 15.

As will be seen, when the lid 42 is closed, it seats upon the top edge of the trough member, thus bringing the cover 28 down upon and into engagement with the top of the receptacle 9, forming a closure for said receptacle. Although the lid 42 is secured in fixed 40 position upon the trough as hereinafter described, yet the cover 28 is at the same time permitted to rotate freely upon the rotation 45 of the receptacle 9.

A conventional latching means is employed 50 for maintaining the lid 42 in closed position and such means may consist of a pair of laterally projecting lugs 45 carried by the lid 42 diametrically opposite the hinge therefor. The lugs 45 are grooved in the tops thereof transversely, to provide seats. Directly below the lugs 45 and secured to the frame 15 55 is a locking member comprising a fixed lug 46 having a cam face on the underside thereof as indicated at 47. Said lug is formed with a vertical opening therethrough adapted to receive a bolt 48 loosely mounted therein, said bolt being formed with a transverse head 49 on the upper end thereof and a nut 50 on the lower end thereof. Said head 49 is provided 60 with a horizontal opening therethrough adapted to receive a shackle 51 so that said shackle will be swingingly pivoted to said head. Upon the said bolt 48 and beneath

said lug 46 is loosely mounted a latch 52 having a cam face 53 upon the upper side thereof to cooperate with the opposed cam face 47 of the lug 46, said latch being formed with a handle 54.

From the foregoing, it will be seen that when the lid 42 is closed, and the handle of the locking member is thrown to release position, the shackle 51 may be swung up and over and into the engagement with the lugs 45, and that thereupon, by swinging the handle of the latch member so as to bring the cam faces into binding engagement, the bolt and shackle secured thereto will be forced downwardly thus causing the lid to be 70 latched or locked into engagement with the trough member.

Thus the lid and trough members are locked against rotation when the receptacle is rotated, still the locking is not so tight that 75 the trough member may not be manually adjusted to a certain degree even when the lid is locked.

While any power mechanism and control means therefor may be employed to rotate 80 the receptacle 9 for the purpose of imparting a centrifugal action to whatever may be contained therein, still I have illustrated and will now describe the preferred mechanism for 85 this purpose.

A clutch mechanism is provided which has a dual function, one of which is to form the connection for rotating the receptacle connected therewith as hereinafter described, and the other is to act as a brake so that stopping the rotation of the receptacle will be 90 gradual and prevent damage thereto.

The aforesaid operating mechanism comprises a stationary collar 55 depending from the platform 5, the lower outer periphery of 95 said collar being beveled upwardly and outwardly. Secured to the bottom of the receptacle 9 and adapted to pass downwardly through said collar 55 is a rotatable shaft 56. Interposed between the inner wall of the collar 55 and the shaft 56 adjacent the upper end thereof, is mounted a ball bearing member 57 to permit free rotation of the shaft and receptacle secured thereto with relation to said collar and the platform 5. Beneath 100 the collar and keyed to the shaft is a clutch member formed with a central sleeve 58, having at its upper end an outwardly and upwardly extending brake shoe 59 beveled upwardly and outwardly upon the inner periphery thereof and adapted to engage with the outer beveled surface of the collar 55. Said sleeve 58 is also formed at its lower end with an outwardly and downwardly extending clutch shoe 60 beveled downwardly and inwardly on its outer periphery and adapted to coact with a beveled gear 61 loosely mounted upon said shaft 56 for the purpose of driving the latter. The gear 61 is provided with 105 an upwardly extending circumferential 110

flange 62 beveled on its inner periphery upwardly and outwardly for engagement with the outer beveled face of the lower clutch shoe 61 of the sleeve 58. A vertically disposed 5 beveled gear 63 is fixed to a shaft 64 operatively connected with the motor 8 and adapted to mesh with the gear 61. Interposed between the top of the sleeve 58 and the bottom of the ball bearing member 57 is an expansion 10 spring 65 adapted to normally hold the clutch member in engagement with the gear 61. A circumferential flange 66' depends from the platform 5 spaced apart from the collar 55 and to which is secured by suitable 15 means a housing 66 which encloses the aforesaid gearing and clutch member, said housing being adapted to retain oil for the constant lubrication and easy operation of the parts. The shaft 56 is hollow and within 20 said shaft is mounted a water inlet pipe 67 having a beveled valve seat 68 at the upper end thereof adapted to retain a ball valve 69 to prevent the discharge of water from the receptacle through the inlet pipe, but at the 25 same time permitting the inlet of water from the pipe to the receptacle. A water pipe, not shown, is connected at one end to the inlet pipe 67 at 67' and at its other end to a source of water supply. A convex perforated plate 30 70 is secured to the bottom of the receptacle 9 adapted to limit the upward movement of the ball valve, permit the ingress of water to the receptacle, and prevent the egress of any solid substance that might otherwise clog the 35 valve.

The shifting means for the clutching member may be of any conventional type, but I have illustrated and will describe a preferred form of such means and it comprises a rock 40 shaft 71 extending through the housing 66', provided intermediate its ends with a bifurcated crank arm 72 for straddling the sleeve 58 whereby when the shaft 71 is rocked in one direction the crank arm will engage with the 45 underside of the brake shoe 59, thus forcing the clutch member 58 upwardly against the normal expansion of the spring 65, causing the said brake shoe of the clutch member to frictionally engage with the collar 55, producing 50 a braking action to gradually stop the rotation of the receptacle. At the same time the clutch shoe 60 of the sleeve 58 is disengaged from the flange 62 of the gear 61, thus disconnecting the clutch member entirely 55 from the motor. A pull rod 73 is secured to a crank 74 carried by one end of the shaft 71 exteriorly of the housing 66'. The rod 73 extends upwardly and is connected to a 60 pivotally supported counterbalanced handle member 75 therefor.

What I claim is:

1. In an apparatus for the purpose set forth a vertically disposed revoluble receptacle forming a combined rinsing and drying chamber, an adjustable drain board, means

carried at the top of the receptacle to permit of adjustably positioning said board circumferentially with respect to the receptacle for directing the overflow from said chamber to the point desired. 70

2. An apparatus for the purpose set forth comprising a washing chamber, a combined rinsing and drying chamber, and a revoluble support carried at the top of the combined rinsing and drying chamber and provided with a drain board capable of being shifted by the support to extend over the washing chamber for directing the overflow from the combined rinsing and drying chamber into the washing chamber. 75

3. In an apparatus for the purpose set forth, a vertically disposed revoluble extracting receptacle flanged outwardly at its upper end to provide a bearing surface for a lid, a separable driving connection for the lower end of said receptacle, a troughed member having an open upper end surrounding the upper end of said receptacle and manually adjustable about the axis for directing water expelled thereinto from said receptacle to the point desired, a drain board connected to and adjustable with said troughed member, a supporting means for said troughed member, a cover for the open upper end of said trough member, and a lid revolvably connected with said cover and adapted when said cover is in closed position to assume a closed position with respect to said receptacle and have an engaging relation with the flanged end thereof, said lid and flanged portion of said receptacle being so related to each other as to provide water egress passage therebetween. 90

4. In an apparatus for the purpose set forth, an extractor comprising a container unobstructed interiorly thereof, operating means connected with said container, and a water conducting element adjacent the upper part of said container and circumferentially adjustable about the same to receive and direct water expelled from said container to one of a selected point of discharge. 105

5. In an apparatus for the purpose set forth, a centrifugal extractor comprising a rotatable receptacle, a cover for the receptacle, circumferentially adjustable means for the discharge of overflow water at the top of the receptacle, said means permitting of the discharge of the liquid selectively at one or another of a plurality of points spaced circumferentially about the receptacle, and means independent of said receptacle for supporting said cover for rotation with the receptacle. 115

6. In an apparatus for the purpose set forth, a rotatable extracting receptacle, an element supported to be manually and circumferentially adjusted about said receptacle and to receive and conduct water therefrom, and water delivery means connected to and adjustable with said element. 125

7. In an apparatus for the purpose set forth, a rotatable extracting receptacle, a housing supported to be manually and circumferentially adjusted about the upper end of said receptacle and to receive and conduct water therefrom, a drain board connected to and adjustable with said housing, a cover for said housing, and a lid rotatably connected with said cover and adapted when said cover is in closed position to serve as a closure for and to rotate with said receptacle.
8. In an apparatus for the purpose set forth, a rotatable extracting receptacle, a housing supported to be manually and circumferentially adjusted about the upper end of said receptacle and to receive and conduct water therefrom, a drain board connected to and adjustable with said housing, a cover for said housing, and a lid rotatably connected with said cover and adapted when said cover is in closed position to serve as a closure for and to rotate with said receptacle, the latter and the lid being related to each other to provide water egress passages therebetween.
9. In an apparatus for the purpose set forth, a rotatable extracting receptacle, a separable driving connection for the base of said receptacle, a drain board supported to be manually and circumferentially adjusted about the upper end of said receptacle, whereby said drain board may be brought into relation with differently placed receptacles, and means to conduct water expelled from said receptacle to said drain board when in its different adjusted positions.
10. In an apparatus for the purpose set forth, a rotatable extracting receptacle, a drain board supported to be manually and circumferentially adjusted about the upper end of said receptacle, whereby said drain board may be brought into relation with differently placed receptacles, means to conduct water expelled from said receptacle to said drain board when in its different positions, and means for supplying water to said receptacle.
11. In an apparatus for the purpose set forth, a vertically disposed revolute receptacle forming a combined rinsing and drying chamber, a drain-board-supporting member surrounding the upper end of the receptacle and adjustable about the axis thereof for directing the overflow from said chamber to the point desired, and means for supporting said member.
12. In a centrifugal clothes drier, a receptacle for the clothes revolute about a vertical axis, and provided at its upper end with an overflow passage, and a conduit encircling the upper end of the receptacle for receiving the overflow, said conduit having an outlet and being adjustable about said axis for directing the outlet to different points.
13. In a centrifugal clothes drier, a receptacle for the clothes revolute about a vertical axis and provided at its upper end with an overflow passage, and means extending laterally from the upper end of the receptacle to receive overflow from said passage and adjustable about the axis of the receptacle to direct said overflow to different points.
- In testimony whereof, I affix my signature hereto.
- HAROLD F. VIEAU. 75
